UNITED STATES PATENT OFFICE.

WILLIAM W. DEAN, OF CHICAGO, ILLINOIS, ASSIGNOR, BY MESNE ASSIGNMENTS, TO
BENJAMIN ELECTRIC MANUFACTURING COMPANY, OF CHICAGO, ILLINOIS, A COR-
PORATION OF ILLINOIS.

SWITCH.

1,255,084.

Specification of Letters Patent. Patented Jan. 29, 1918.

Application filed February 18, 1913. Serial No. 749,135.

To all whom it may concern:

Be it known that I, WILLIAM W. DEAN, a citizen of the United States, residing at Chicago, in the county of Cook and State of Illinois, have invented new and useful Improvements in Switches, of which the following is a full, clear, concise, and exact description, reference being had to the accompanying drawing, forming a part of this specification.

My invention relates to improvements in electric switches which are capable of being positively operated without particular care or attention on the part of the operator. In many situations it is desirable to have a switch which is positive in its action and which at the same time may be operated without taking the attention of the operator from other things that he may be doing. In other places it is desired to have a switch that is positive in its action regardless of at what point or from what direction the operating pressure is applied, or whether operated by the pressure of the whole hand or of the thumb or finger. In other cases the switch may be covered and not exposed to view and it is necessary to operate it through some intervening material or fabric. In such cases it is desirable to have a switch that will respond to pressure regardless of how directly or indirectly it may be applied.

In my invention I have provided a switch especially adapted for all such uses, although it may be used for switching purposes generally.

I have illustrated one embodiment of the invention in the accompanying drawings, in which—

Fig. 1 represents the switch applied to the steering wheel of a vehicle;

Fig. 2 is a side elevation showing the spider arm of the steering wheel in cross-section, such cross-section being taken on the line 2—2 of Fig. 1;

Fig. 3 is a cross-sectional elevation taken on the line 3—3 of Fig. 1;

Fig. 4 is a cross-section of the same switch taken on the line 4—4 of Fig. 1; and

Fig. 5 is a sectional plan view taken on the line 5—5 of Fig. 4; each of such views illustrating the sections looking in the direction of the arrows.

Within a shallow cup or casing 10, preferably stamped from sheet brass, is secured

a fiber or insulating disk 11 forming a base or support for the electrical parts of the switch. This base is secured in position by two screws 12 passing through the bottom of the casing 10 and threading into the said base.

On the upper face of this disk or base 11 is mounted a flanged ring member 13, also preferably stamped from thin sheet brass and forming one of the coöperating contacts of the switch. This switch member is firmly secured concentrically of the base 11 by suitable rivets 14 passing through the base and the flange of the ring 13, as indicated.

Within the opening of the flange of this contact ring 13 and on the upper face of the base 11 is mounted and rigidly secured a metallic disk 15, by two screws 16 passing through the base and threading into the disk itself. This disk 15 is spaced apart from the flange of the ring 13 so as to be insulated electrically therefrom. To the center of this disk 15 is rigidly secured, by riveting or otherwise, a stud or post 17 having a flat head 18. A plate or disk 19 slightly larger in diameter than the ring 13 is mounted on this post 17, and a coil spring 20 surrounds this post between the lower side of the plate 19 and the upper side of disk 15. The tension of the spring tends to raise the plate 19 against the head of the post 17, the construction and arrangement being such that normally the plate is held out of contact with the edge of the ring 13. The opening in the plate 19 is slightly larger in diameter than the post 17, to allow sufficient clearance so that the plate can readily move longitudinally on the post or tip slightly at an angle thereto.

This plate 19 forms the other coöperating contact of the switch, and, as just explained, is so arranged as to be moved bodily toward the edge of the ring in response to pressure centrally applied thereto or to be tipped sidewise at any point toward said ring in response to pressure peripherally applied, and by peripherally I mean any pressure which is not central. In either case the contact will be brought into physical engagement or contact with the edge of the ring 13, thus closing the switch contacts and thereby completing the electric circuit controlled by the said switch. The contacts shown are "butt" contacts, that is to say, when the contacts are closed the movable contact abuts 110

against the stationary contact so that there is no frictional engagement between the contacts to oppose the separation of the contacts due to the action of the spring when pressure on the operating member or button is released.

For the purpose of suitably operating said switch, I provide the same with a suitable operating member or button consisting in the present instance of a cover or cap plate 21 secured to said plate by screws 22, which cap is preferably of hard rubber or other insulating material and is provided with a depending flange at its edge fitting down over the edge of the casing 10. The outside of the cap is preferably oval, as shown, and if desired may be suitably chased or otherwise finished.

A central depression in the lower side of the cap affords a clearance for the head 18 of the post 17 when said cap is pressed downwardly or tipped sidewise. This cap thus forms a cover for the casing 10 in which the operating members of the switch are contained and inclosed. The outward movement of the cap or button is limited by the head of the post 17. It is apparent that pressure applied to this button or cap at any point and from any direction serves to operate and close the switch contacts and that when such pressure is removed the spring 20 serves to return the button or cap to normal position and open said contacts. When pressure is applied to the center of the button the button moves rectilinearly or bodily toward the base. When peripheral pressure, that is, pressure at any point about the center or axis of the button, is applied to the button or cap, the plate 19 finds a fulcrum on the head 18 of the post 17 at a point diametrically opposite the point of application of pressure, and this fulcrum point is capable of shifting around the circumference of the head 18, the fulcrum point depending upon the point of application of pressure. Irrespective of where pressure is applied to the button, whether at the center or at any point around the axis of the button, the circuit is controlled through the medium of the operating contacts.

Furthermore, the button is rotatably mounted, so that in event the contact surfaces become fouled the button can be depressed, forcing one contact into engagement with the other, and then rotated, thereby grinding the contacts together and cleansing their contacting surfaces to insure a good electrical connection.

As indicated in Figs. 4 and 5, the binding screw 23 serves as a medium for connecting one of the electric conductors to the terminal or contact 12, and the lug 24 extending from the disk 15 through a suitable aperture or slot 25 in the edge and flange of the ring 13, serves to enable the other conductor to be

connected by a binding screw 26 to the other terminal or contact of the switch, the path for the current in the latter case being through the disk 15, spring 20 and post 17 to the plate 19. After being connected to their respective terminals, the conductors may be brought out through an aperture in the edge of the casing 10, as indicated in Fig. 2 and Fig. 5.

While the invention as thus disclosed is capable of use for various purposes, it is particularly applicable to uses where the operator may not be able for various reasons to exercise care as to the particular manner of applying pressure or force to operate the switch, or where he cannot conveniently do so without having his attention distracted from other matters to which it should be directed.

I have illustrated in Fig. 1 one use to which this form of switch is particularly adapted. In this figure a steering wheel 27 is shown with the switch mounted on one of the spider arms 28. The switch rests on the top of the arm and a clasp 29 passes beneath the arm and is secured to the casing 10 by means of screws 30, which when tightened clamp the switch firmly to the arm. A horn or other signal is diagrammatically indicated at 31, and the circuit and source of current are likewise diagrammatically indicated. The switch is preferably located close to the rim of the wheel, whereby it is within reach of and may be readily operated by the thumb of the driver without causing him to release his grip upon the rim of the wheel. This is particularly valuable in an emergency, when the driver may not have the time to let go of the rim and reach for the switch, or when he dare not release his grip on the steering wheel for that purpose.

When the driver of the vehicle wishes to sound the alarm, he applies pressure to the cap of the switch in the most convenient manner. He may do this by bearing directly down upon it with the thumb or the hand, or he may press in an angular direction upon one point of it with the hand or with the thumb or finger, and he may use either hand in all of these ways. In an emergency he may suddenly strike the switch from almost any direction and with either hand. In all such cases the cap will respond, either by tipping or bodily moving downwardly, and thus close the switch and sound the alarm. The presence of heavy cumbersome gloves or mittens on the hands is no obstacle to the operation of the switch, since the operator is not required to locate a small button, as is common, and press upon it in a particular manner and direction in order to give an alarm.

It is apparent also from the foregoing that the switch may be conveniently and cheaply manufactured and installed, is

strong and durable, and is not liable to derangement by rough usage.

While I have thus described one form of my invention and one arrangement of contacts and one manner of operating the switch, it will be apparent to those skilled in the art that it may be embodied in various forms and arrangements and be operated in various ways and still fall within the spirit 10 and scope of the appended claims.

Having thus described my invention, what I claim as new and desire to secure by Letters Patent is—

1. In an electric switch, the combination 15 with coöperating switch contacts, one of said contacts being circular in form and the other adapted to be brought into engagement with said circular contact at any point to close the electric circuit, of operating means connected with said contacts having a rectilinear and tilting movement and arranged to bring the contacts into engagement by either movement to close the electric circuit.

2. In an electric switch, the combination 25 with a casing, of an insulating base within said casing, a ring contact mounted on said base, a cover for the casing, and a contact plate mounted on the inner side of the cover, and yielding supporting means for said plate 30 and cover normally holding said plate out of contact with the edge of the ring, and permitting the cover to move bodily toward the base or be tilted with respect thereto to press the plate by either movement into contact with the edge of the ring to complete the electric circuit.

3. The combination with an insulating base, an annular contact mounted on said base, a binding-post for said contact, a second binding-post mounted on said insulating base, a movable contact arranged to engage said annular contact at any point around its circumference, and a coiled spring interposed between said contacts tending to 45 separate the same, engaging said movable contact and electrically connecting the same with said second binding-post.

4. The combination with an inclosing casing, of an insulating base mounted within 50 said casing, an annular contact mounted on said insulating base, a binding-post for said contact, a second binding-post mounted on said base, a movable cover for said casing, means for preventing said cover from being 55 entirely separated from said casing, a contact plate mounted on the under side of said cover, and a coiled spring tending to separate said contact plate from said annular contact engaging said contact plate and electrically connecting the same with the second binding-post mounted on said base.

5. In an electric switch, the combination 60 with a pair of spaced-apart contacts having annular contacting surfaces, one of said contacts being movable relatively to the other,

and a central fulcrum member for said movable contact, said movable contact having a rectilinear and tilttable movement and engaging the other contact by either of said movements.

6. In an electric switch, the combination 70 with an insulating base, of a contact on said base having an annular contacting surface, a binding post for said contact, a movable contact substantially parallel with said first mentioned contact having an annular contact surface coöperating with the contact surface of the opposite contact, a second binding-post on said base, and a coiled spring tending to maintain said contacts in 80 substantial parallelism and electrically connecting said movable contact with said second binding-post.

7. An electric switch comprising a casing, 85 a contact-actuating member movable bodily toward said casing to contact-closing position by pressure applied at the center thereof and tilttable relatively to said casing by pressure applied about said center, and coöperating switch contacts in said casing 90 relatively movable into and out of electrical engagement at different points of said contacts in response to different movements of said member.

8. In an electric switch, the combination 95 with a cup-shaped contact member, of a flat contact member having an annular contacting surface, resilient means centrally disposed tending to separate said members while permitting a relative rectilinear and 100 tilting movement of the members to cause said contacts to engage, and means for preventing said members from becoming unduly separated.

9. In an electric switch, the combination 105 with a casing, of a cover therefor overhanging the edges of the casing, an insulating base in said casing, a contact member mounted on said base having an annular contact surface and a contact member mounted on 110 said cover having an annular contact surface coöperating with the surface of the contact mounted on the base, resilient means tending to separate said cover from the casing while permitting the cover to be moved toward the casing and the contacts engaged under the influence of central or peripheral pressure, and means for preventing the cover from being entirely separated from the casing.

10. An electric switch comprising a stationary and a movable member, the stationary member carrying a pair of terminals for the switch, the movable member having a rectilinear and tilttable movement to operate 125 the contacts of the switch, one of said members having a locking plate provided with a central opening, the other member having a central post extending through said opening provided with an annular shoulder there- 130

on engaging behind the plate and a spring tending to separate said members.

11. In an electric switch, coöperating switch contacts, a contact-actuating member rectilinearly movable to contact-closing position by pressure applied at its center and tilttable by pressure applied about its center, and a fulcrum member on which the operating member fulcrums when tilted, the 10 point of electrical contact being radially outside of and beyond the fulcrum member.

12. In an electrical switch, coöperating circuit making and breaking contacts, a contact-actuating member rectilinearly movable 15 to contact-closing position by pressure applied at its center and tilttable by pressure applied about its center, and a fulcrum member on which the contact controlling member fulcrums when tilted, the location of the 20 point of fulcrum depending upon the point of the application of pressure on the operating member, the contacts being radially outside the periphery of the fulcrum member.

13. An electric push button comprising 25 terminals normally spaced apart, a case supporting said terminals, said case comprising peripherally telescoping sections, yielding means normally holding said sections coaxial, means for preventing separation of 30 said sections and for preventing telescoping movement beyond a predetermined point, said sections being relatively movable both axially and out of coaxial relation to bring said terminal members into circuit closing 35 relation.

14. In a push button device, a skirted push button having an annular catch thereon, a stationary member having an annular catch thereon, said catches being in engagement throughout their peripheries, said skirt 40 overhanging the stationary member and said push-button, being rockable with respect to the stationary member about any point of said periphery, spring means between said 45 push-button and member permitting the depression of the push-button, and a switch operated when said push-button is rocked down about any point on the peripheries of the catches or depressed down.

15. In a circuit controller, the combination of a stationary member and a skirted movable member, slideable and tilttable with reference thereto and having the skirt overhanging the margin thereof, guiding means 55 controlling said movable member as it slides with respect to said stationary member, and a plurality of fulcrums about which said movable member tilts with respect to said stationary member, and an electric switch 60 controlled by said movable member and operated by sliding or tilting said movable member with respect to said stationary member.

16. In a circuit controller, the combination 65 of a stationary member and a movable

member, a central bolt for connecting said members together, yielding means normally holding said members in spaced relation, said means permitting said movable member to be either rocked or slid with respect to said stationary member, and a switch operated by rocking or sliding the movable member with respect to the stationary member.

17. In a circuit controller, the combination 75 of a stationary member and a movable member, means including a central bolt and a catch for connecting said members together, a spring between said members normally holding said members in spaced relation to each other, said means permitting said movable member to be either rocked or slid with respect to said stationary member, and a switch operated by rocking or 80 sliding the movable member with respect to 85 the stationary member.

18. In a circuit controller, the combination 90 of a stationary member and a movable member, a switch having two contacts, one on each member, a perforated plate carried by one member, a bolt carried by the other extending loosely through said perforated plate and slideable therein, a catch member on one end of the bolt retaining it in position in said perforation, an abutment on the 95 bolt, a spring between the abutment and the plate normally holding said members with the contacts of the switch separated, said switch being closed when either of said members is either rocked or slid with respect 100 to the other.

19. In a circuit controller, the combination 105 of a stationary member and a movable member, an electric switch comprising a pair of contacts, one of which is mounted on each of said members, means including a central bolt and a catch for slidably and rockably connecting said members together, and yielding means between said members normally holding said contacts separated, said yielding means permitting the sliding and rock 110 ing of one of said members with respect to the other to close the switch.

20. In a circuit controller, the combination 115 of a movable member and a stationary member, a normally open switch comprising two contacts, one carried by each of said members, means including a central bolt and a catch for slidably and rockably connecting said members together, a spring normally 120 holding said members in position with the switch open, said spring permitting one of said members to be either slid or rocked with respect to the other to close the switch.

21. An electric switch comprising a cas 125 ing, circuit connections in said casing, a centrally disposed switch member for controlling said circuit connections, and a pressure operated member marginally overhanging said casing and having a tilttable and 130

rectilinear movement for operating said switch member.

22. In an electric switch, the combination with an insulating base, of a contact mounted on said base having an annular contact surface projecting above the surface of said base, a cap spaced apart from said base, a contact mounted on the underside of said cap having an annular contact surface co-10 operating with the contact surface of the contact mounted on the base, a spring interposed between said cap and base for maintaining the same normally spaced apart, and means for connecting said base and cap which permits the cap to be moved toward the base by a tilting or vertical movement.

23. A tipping push switch comprising a casing member, circuit-controlling elements inclosed thereby, a top or cover for said casing member having a tilting and rectilinear movement to operate said controlling elements to close the circuit and having a periphery overhanging the periphery of the casing member, and a mounting for said 20 top or cover permitting the tilting of the same when the periphery is subjected at any point to a glancing or oblique side blow or pressure.

24. A tipping push switch comprising a 30 casing member, circuit-controlling elements inclosed thereby, a top or cover for said casing member, having a tilting and rectilinear movement to operate said controlling elements to close the circuit, said top or cover having its periphery overhanging the periphery of said casing member and provided with an outwardly extending skirt sufficiently removed from the exterior wall of said casing member to accommodate the 35 tilting of said top or cover, and a mounting for said top or cover permitting the tilting of the same when the periphery is subjected at any point to a glancing or oblique side blow or pressure.

25. A tipping switch comprising a casing member, circuit-controlling elements inclosed thereby, a top or cover for said casing member having a universal tilting movement to operate said controlling elements to 50 close the circuit and having a periphery overhanging the periphery of the casing member, and a mounting for said top or cover permitting the tilting of the same when the periphery is subjected at any point to a glancing or oblique side blow or pressure.

26. A tipping switch comprising a casing member, circuit-controlling elements inclosed thereby, a top or cover therefor having a universal tilting movement to operate 60 said controlling elements to close the circuit, said top or cover having its periphery overhanging the periphery of said casing member and provided with an outwardly extending skirt sufficiently removed from the ex-

terior wall of said casing member to accommodate the tilting of said top or cover, and a mounting for said top or cover permitting the tilting of the same when the periphery is subjected at any point to a glancing or 70 oblique side blow or pressure.

27. A tipping switch comprising a casing member, a stationary circuit contact, arranged within said casing member, a top or cover for said casing member having a universal tilting movement and rotatable with respect to said stationary contact, a contact mounted on the under face of said top or cover for engagement with said stationary contact for closing the circuit and arranged 75 to be ground, by the rotation of said cover, against said stationary contact for cleaning the contact faces, and a mounting for said top or cover permitting the tilting and rotation of the same.

28. A tipping top switch comprising a casing, circuit controlling elements inclosed by said casing, the width of the casing being greater than the element inclosing depth thereof, a tipping top or cover for said casing having its hand engaging portion above the casing and of substantially the same or greater width, and a mounting for said top or cover permitting the tipping of the same, when struck by the hand, to operate 90 said circuit controlling elements.

29. A tipping push top switch comprising a casing, circuit controlling elements inclosed by said casing, the width of the casing being greater than its element inclosing 100 depth, a tipping and rectilinear movable top or cover for said casing having its hand engaging portion above the casing and of substantially the same or greater width, and a mounting for said top or cover permitting 105 the tipping and rectilinear movement of the same, when struck by the hand, to operate said circuit controlling elements.

30. In an electric switch, a pair of co-operating members having annular engaging portions, one of which is mounted in a stationary position, a depressible and tilt-able overhanging button on which the other member is mounted and which finds a fulcrum with respect to the other member when 110 the button is tilted irrespective of where tilting pressure is applied, co-operating switch contacts controlled by said button, and means for restoring the button to its inactive position when pressure thereon is relieved.

31. A tipping switch comprising a stationary contact, a contact-actuating member having a universal tilting movement with respect to said stationary contact and rotatable with respect to said stationary contact, a contact mounted on the under surface of said actuating member for engagement with said stationary contact for closing the circuit when the actuating member is operated 125 130

and arranged to be ground against said stationary contact by the rotation of said movable member to clean the contact surfaces, and a mounting for said movable member 5 permitting said universal tilting movement and the rotation of the same.

In witness whereof, I have hereunto sub-

scribed by name in the presence of two witnesses.

WILLIAM W. DEAN.
